P. J. CALLOWHILL

VANITY CASE

Filed June 20, 1925

FIG. 1.

Inventor

Percy J. Callowhill

By Joseph A. Miller

Attorney

UNITED STATES PATENT OFFICE.

PERCY J. CALLOWHILL, OF PROVIDENCE, RHODE ISLAND, ASSIGNOR TO THEODORE W. FOSTER & BROTHER COMPANY, OF PROVIDENCE, RHODE ISLAND.

VANITY CASE.

Application filed June 20, 1925. Serial No. 38,461.

This invention relates to certain new and useful improvements in vanity cases, and the primary object thereof is to provide a vanity case wherein same may be opened and closed with but one hand and upon opening the mirror will be automatically projected outward, and upon closing, will be automatically moved into the case.

A further object of the invention is to provide a structure wherein the mirror is moved into the case by mere engagement therewith of either the cover or body of the case and also to provide a structure wherein the mirror holds the body and cover firmly apart or at the limit of their extended positions.

In the drawings:—

Figure 1 is a plan view of the invention, and

Figure 2 is a side elevation thereof.

In proceeding in accordance with the present invention, a body 1 is employed having a cover 2 hinged thereto at 3. Powder or rouge of varying or desired color is placed in the cover and body, the usual powder pads D, D' being employed. The cover has a retaining bar 4, to removably secure its pad in place.

A mirror 5 is secured by a spring hinge 6 to the body 1 at an angle to the axis of the hinge 3 so that the periphery of the mirror frame will engage the pad D' and the rim of the cover.

In operation, when the latch L is released by the thumb of the user, the mirror under the impulse of the spring of its hinge, will engage the pad D' and ride thereover, having a camming action on the cover to force the latter to its limit of opening, in which position, the parts will be held as depicted in the drawings, wherein the mirror extends across the line of hinging of the body and cover and outwardly of same at an angle. To close the case, the fingers are moved to cause the cover to move to normal position, which movement effects a similar camming action of the pad D' on the periphery of the mirror whereby the latter is automatically moved to completely lie within the case, or between the body and cover.

From the foregoing it will be seen that by merely grasping the case in one hand and with the thumb engaging the body and used to release the latch, and with the fingers en-

gaging the cover, the case may be opened and closed easily and quickly and with but use of one hand.

It is to be noted that in full open position of the body, cover and mirror all face the user and occupy substantially parallel relation, and are arranged in triangular formation, the mirror being disposed between the body and cover. Thus the user has complete and convenient access to either the powder or the rouge carried by the body and cover without changing the position of the parts when in the position depicted in the drawings, and without any movement of the hand beyond movement to shift the hand from the body to the cover or vice versa.

Having thus described my invention what I claim as new and desire to secure by Letters Patent is:—

1. In a vanity case, a body, a cover hinged to the body, a mirror, means to connect the mirror to one of the first two named elements so as to overlie the other elements when the parts are in full open position whereby in such open position of the elements the body, cover and mirror each face the user and all lie in substantially parallel relation and means to actuate the mirror and thereby move the other element to full open position and upon closing movement of the said other element to enable the latter to automatically move the mirror into the body.

2. In a vanity case, a body, a cover hinged to the body, a mirror, means to connect the mirror to one of the first two named elements so as to overlie the other element when the parts are in full open position whereby in such open position of the elements the body, cover and mirror each face the user and all lie in substantially triangular relation and with the mirror extending outwardly beyond the body and cover and means to actuate the mirror and thereby move the other element to full open position and upon closing movement of the said other element to enable the latter to automatically move the mirror into the body.

3. In a vanity case, a body, a cover, means to movably connect the body and cover, a mirror, and means to connect the mirror to one of the two first named elements so as to cause the mirror to have camming engagement with the other element in both

opening and closing of the case whereby the case may be completely opened and closed by the use of but one hand.

4. In a vanity case, a body, a cover therefor, means to movably connect the cover to the body, a mirror, and means to movably connect the mirror to one of the two first named elements and with the mirror arranged to have a part thereof engage the other of said two first named elements in both full open and closed position of the parts so as to actuate and be actuated by the latter.

5. In a vanity case, a body, a cover therefor, means to movably connect the cover to the body, a mirror, and a spring hinge to movably connect the mirror to one of the two first named elements and with the mirror arranged to have a part thereof and continuously to cammingly engage the other of said two first named elements so as to actuate and be actuated by the latter.

6. In a vanity case, a body, a cover hinged thereto, a mirror, and means to movably mount the mirror on one of the said parts whereby to effect positive and complete outward movement of the other part by the mirror and retention thereof in the full open position and inward movement of the mirror by said other part in opening and closing of the case.

7. In a vanity case, a body, a cover, means

to movably connect the cover to the body, a mirror, means to connect the mirror to one of the first two named elements so as to be movable into and out of the case and to overlie and positively hold the other of said elements at its limit of outward movement when the mirror is disposed out of the case, and means to effect automatic movement of the mirror out of the case upon opening of the case.

8. In a vanity case, a body, a cover, means to movably connect the cover to the body, a mirror, and means to connect the mirror to one of the first named elements whereby the case may be completely opened and closed by use of but one hand and upon opening or closing the mirror will be automatically moved out of and into the case, the body and cover both lying substantially tangential to the mirror in open position of the parts.

9. In a vanity case, a body, a cover, means to movably connect the body and cover, a mirror and means to connect the mirror to one of the two first named elements so as to cause the mirror to have engagement with the other element in all positions of the mirror whereby the case may be completely opened and closed by use of but one hand.

In testimony whereof I have signed my name to this specification.

PERCY J. CALLOWHILL.
